SHOE

Frank Parlante, Brooklyn, N. Y.

Original application May 15, 1931, Serial No. 537,726. Patent No. 1,864,506, June 21, 1932.
 Divided and this application May 18, 1932.
 Serial No. 612,106

7 Claims. (Cl. 36—45)

An object of the invention is to provide a shoe having a heel and a shank, with the upper of the shoe extending downwardly under the shank and against the outer surface of the heel to give a neat appearance and to assist in securing the heel in place.

Another object of the invention is to provide a shoe with a heel having opposite sides which converge downwardly and against which the upper fits snugly to secure the heel in position.

Still another object of the invention is to provide an upper having side pieces extending down under the shank of the shoe and at the front, the back and the sides of the heel, with the side pieces 15 of the upper secured together under the shank and between the sides of the heel.

Additional objects of the invention will appear in the following specification in which the preferred form of the invention is described.

20 In the drawing similar reference characters refer to similar parts in all the views, of which

Figure 1 is a side elevation of the shoe, the shoe being shown in section on the lines 1—1 of Figure 2,

25 Figure 2 is an inverted plan view of the shoe, Figure 3 is a rear view of the shoe, and

Figure 4 is a fragmentary view illustrating the front of the heel.

30 This application is a division of patent application Serial No. 537,726, filed May 15th, 1931 which has matured into Patent No. 1,864,506, granted June 21, 1932.

By referring to the drawing, it will be seen that the shoe 5 has a shank 6, a counter 7 and a heel 8, the heel 8 being secured to the counter 7, and the shank 6 also being preferably secured to the counter 7. As will be seen by referring to the drawing, the heel 8 decreases in cross area downwardly.

40 The shoe 5 has an upper 9, the saddle portions 10 of which extend under the shank 6 and down against the front 11 of the heel 8, the sides of the upper also extending down at 12 against the sides and the back of the heel 8, forming with the front 11 a sleeve for the heel. The saddle portions 10 of the upper are secured together by stitching at 13 longitudinally of the shoe and under the shank 6, the stitching continuing down at 14 at the front of the heel. The saddle portions 10 of the upper 9 are also secured together at the back of the counter 7 at 15 and at the back of the heel 8 at 16. In this manner the heel 8 has its front, sides and back enclosed by the upper 9, which gives a neat appearance and which serves to securely hold the heel to the counter 7,

the upper passing under the shank 6 in the manner described.

Inasmuch as the heel decreases in cross-sectional area downwardly, the upper disposed around the heel 8 will tend to grip the heel 60 for securing the latter. If desired, the upper may be glued or secured by other adhesive to the heel.

The upper not only extends down at the front, sides and back of the heel in the manner described, with stitching at the front and the rear of the heel, but preferably the upper also extends under the heel 8 at 17 and a tap 18 is disposed against the portions 16 of the upper 70 at the bottom of the heel, the said tap being secured to the heel by nails 19. It will be understood that, with the tap 18 secured to the heel in this manner, it serves not only as a wearing surface, but also serves to hold the upper 75 in place around the heel and the heel in place in the counter 7.

What is claimed is:

1. A shoe having a shank and a heel, and an upper which has side pieces which extend down and under the shank and down and against the walls of the heel, the side pieces being secured together at the shank and between the sides of the heel at the front and rear of the heel.

2. A shoe having a shank and a heel, and an upper with side pieces which extend down against the shank and against the front, side and back walls of the heel, the said side pieces being secured together under the shank and at the front and at the back of the heel.

3. A shoe having a shank and a heel, and an upper with side pieces which extend down and cover the front the sides and the back of the heel, the said side pieces being secured together under the shank between its sides and at the front and at the back of the heel between the sides of the heel.

4. A shoe having a shank and a heel, and an upper with side pieces which extend down under the shank and cover the front the sides and the back of the heel, the said side pieces being secured together between the sides of the shank and between the sides of the heel.

5. A shoe having a shank and a heel, and an upper with side pieces which extend down under the shank and against the front side and back walls of the heel, the said side pieces being secured together under the shank and between the sides of the heel.

6. A shoe having a shank and a heel and an upper which has side pieces which extend down

and under the shank and down and around the walls and breast of the heel, the side pieces being secured together at the shank and between the sides of the heel at the front and rear of the heel.

7. A shoe having a shank and a heel, and

an upper having side pieces extending down against and covering the shank, the front, side and back walls of the heel, the said side pieces being secured together under the shank and at the front and at the back of the heel.
